IGNITRON CONTROL SYSTEM FOR CIRCUIT
BREAKERSWilliam E. Pakala, Forest Hills, Pa., assignor to
Westinghouse Electric Corporation, East Pitts-
burgh, Pa., a corporation of Pennsylvania

Application October 30, 1942, Serial No. 463,924

10 Claims. (Cl. 175—294)

1

My invention relates to arrangements for controlling the opening and closure of circuit interrupters and in particular to control of current flow to solenoids of electrically actuated circuit interrupters.

One of the most widely used arrangements for actuating the mechanism of circuit interrupters to move them to their closed-circuit position comprises a magnetic core which is attracted by an electrically energized solenoid to move the circuit interrupter against a spring or other bias to its closed-circuit position. Such a solenoid is, of course, energized by current flow only during the comparatively infrequent intervals when the circuit breaker is actually being moved to closed circuit position. It is also the usual practice to provide such circuit breakers with overload relays which operate, when an overload occurs on the circuit governed by the breaker to upset a toggle thereby permitting the above-mentioned bias to move the circuit breaker to open-circuit position.

After the circuit breaker has thus been opened by the overload relay an attendant usually closes a manually operated switch which sends current from a supply source through the above-mentioned closing-solenoid thereby reclosing the circuit breaker. If now the overload condition on the line governed by the circuit breaker still persists, the overload relay will again trip the circuit breaker to open-circuit position. If the attendant still holds the above-mentioned manual switch closed, the solenoid will again close the circuit interrupter, and this cycle of periodic openings and closings will continue for some time with wear, overheating and other injurious effects to the circuit breaker mechanism. Such repeated operations are known in the art as "pumping."

One object of my invention is to provide a circuit for energizing the closing solenoid of a circuit breaker which will prevent "pumping."

Another object of my invention is to provide an arrangement in which electrical discharge devices are employed to control current flow to the closing coil of a circuit breaker in such a way as to prevent pumping.

Electrical discharge tubes sometimes become freely conductive by ionization, which is probably an electrical breakdown phenomena, in their discharge spaces even when the only voltage impressed across their terminals is one supposedly too low to render them conductive.

Still another object of my invention is to provide a circuit employing electrical discharge devices for controlling energization of the closing

15 solenoid of a circuit interrupter which shall insure that accidental ionization of the discharge space in an electrical discharge device shall not result in unexpected closure of the circuit interrupter.

5 Other objects of my invention will become apparent when reading the accompanying description when taken in connection with the drawing, in which:

10 Fig. 1 is a diagrammatic showing of the circuit for energizing the closing-solenoid of a circuit interrupter from a direct-current supply-source and which employs electrical discharge tubes of the ignitron type;

15 Fig. 2 is a schematic diagram of a circuit for energizing the closing solenoid of a circuit breaker from an alternating current supply-source and using electrical discharge devices of the ignitron type;

20 Fig. 3 is a schematic diagram of a circuit for energizing the closing solenoid of a circuit breaker from an alternating current source and which employs a single electrical discharge tube of the ignitron type provided with a shield-electrode; and

25 Fig. 4 is a schematic diagram of a circuit for controlling current flow to a closing solenoid for a circuit breaker from a direct-current source and using only a single electrical discharge tube therein.

30 Referring in detail to Fig. 1, a circuit breaker 1 which may be of conventional type but is here shown for sake of simplicity as of the single-pole type controls current flow through an alternating-current power line 2. The bridging member 3 of the circuit breaker 1 is biased to open circuit position by any suitable means such as a spring 3 and is moved to closed circuit breaker position by energization of a solenoid 4 enclosing a magnetic core 5 by current flow from a direct-current supply line 6—7. Current flow through

35 the solenoid 4 takes place from the line 6 through a pair of serially connected electrical discharge tubes 8—9 which are preferably of the ignitron type embodying respectively anodes 11—12, cathodes 13—14 and igniter electrodes 15—16. Elec-

40 trical discharge devices of the ignitron type just referred to remain non-conductive notwithstanding the impression across their anodes and cathodes of a voltage of the order of that of the source 6—7 as long as their igniter electrodes 15—16 are not energized by current flow. How-
45 ever, when a sufficient current flows through their igniter electrodes even for a very short time, the path between the anodes and cathodes of tubes 55 such as 8 and 9 are ionized and rendered conduc-

2

tive so that current will flow through them from such a supply-line as 6—7, and will continue to flow even after cessation of current through the igniter electrodes until it is interrupted by reducing the voltage between their anodes and cathodes to a value below a certain critical minimum. Thus in the present case the tubes 8—9 are supposed to remain non-conductive since, as will now be explained their igniter electrodes are not energized; and to be rendered conductive when it is desired to close the circuit breaker 1 by manually energizing their igniter electrodes.

A pair of equal resistors 17—18 are respectively bridged in shunt with the tubes 8—9, their resistances being of a high value, and their purpose being to insure an equal division of voltage of the line 6—7 between the tubes 8—9 when they are in their normal, nominally non-conductive, condition.

The igniter electrodes 16 are respectively connected to the cathode 13 of the tube 8 through a manually operated switch 19, and the igniter electrode 15 of the tube 8 is connected through a second switch 21 which moves simultaneously with the switch 19 to the common terminal of a resistor 22 and a capacitor 23 which are bridged in series with each other between the supply lines 6—7. The resistor 22 is of a relatively high value and serves to maintain the capacitor 23 charged to the full voltage of the supply line 6—7 as long as the switches 19—21 remain open. When it is desired to energize the solenoid 4 to move the circuit breaker 4 from its open to its closed position, the common handle of the switches 19—21 is moved against the bias of their spring 24 to close them.

The capacitor 23 is bridged by a switch 25 which is open while the circuit breaker 1 is opened and closed when the latter is closed. When the circuit breaker 1 is closed the switch 25 short circuits the capacitor 23 and insures that it is maintained in a discharged condition thereby insuring that the capacitor 23 cannot discharge sufficient current to energize the ignitrons 8 and 9 to maintain current flow through the solenoid 4 even should the switches 19 and 21 be accidentally closed while the circuit breaker 1 is in its closed circuit position. The resistor 22 is preferably made large enough in value so that the current flowing through it and switch 25 from the line 6—7 while the circuit breaker 1 is closed does not represent a substantial loss of energy, but is made small enough so as to charge the capacitor 23, when switch 25 and circuit breaker 1 are open, in a time which is small compared with the period elapsing while the mechanism of the circuit breaker 1 is moving at from open to closed position.

As has previously been stated, current would continue to flow through the closing solenoid 4 and the ignitrons 8 and 9 from the source 6—7 for an indefinite period, even though the switches 19 and 21 were released to open position if the circuit contained only the elements so far described. In order to interrupt current flow through the solenoid 4 and the ignitrons 8—9 as soon as the circuit breaker 1 has moved to its closed circuit position, I provide a capacitor 26 which is connected between the anode 11 of the ignitron 8 and the common terminal of a pair of resistors 27—28 which are serially connected across the supply line 6—7 through a switch 29 which is opened while the circuit breaker 1 is opened and closed while it is closed. The capacitor 26 is normally maintained in a substantially discharged condition 75

while the circuit breaker 1 is either standing open or standing closed by reason of the fact that the ignitrons 8 and 9 are non-conductive and there is no voltage drop across the terminals of the solenoid 4. When, however, the ignitrons 8 and 9 are energized to close the circuit breaker 1, current can flow through the resistor 27 through capacitor 26 and ignitrons 8 and 9 to charge capacitor 26 substantially up to the full voltage of the line 6—7, its lower plate being charged positively relative to its upper plate. This condition continues until the circuit breaker 1 closes at which time the switch 29 closes, bridging the capacitor 26 across the two ignitrons 8—9 with such a polarity as to tend to send a current in the reverse direction through them than that which they are already conducting through the solenoid 4. This reduces the voltage drop between their anodes and cathodes far below the critical value which is necessary to maintain current flow through them and their arcs are immediately extinguished and they are rendered non-conductive. They thus remain non-conductive until they are ionized by energization of their igniter electrodes 15—16 by manual closure of the switches 19—21.

The circuit interrupter 1 is provided with an overload relay 31 which upon sufficient energizations by current flow through the line 2 closes a switch 32 which is connected in series with a solenoid 33 which magnetically operates a latch 34. The latch 34 normally holds the circuit breaker 1 in its closed circuit position, once it has been moved thereto by current flow through solenoid 4. Closure of the contacts 32 upon flow of an overload current in the lines 2 energizes the solenoid 33 to trip the latch 34 and permit the circuit breaker 1 to be moved to its open circuit position under the edge of its bias 3. The latch 34 is only symbolical and may be replaced by an overset toggle or other devices commonly employed for similar purposes in the circuit breaker art.

It will be noted that if an overload still exists on the line 2 after the circuit breaker 1 has been reclosed by manual closure of the switch 21, the solenoid 33 will again cause reopening of that circuit breaker. If now the switch 21 is still held in its closed position, there will be no reenergization of the closing coil 4 for the reason that the condenser 23 is virtually short-circuited by the current path through the igniter electrodes and the current flowing through the high resistance 22 is unable to charge the condenser 23 to a substantial voltage. It is only when the switch 21 has been reopened that the condenser 23 can charge up to substantially the line voltage and thereby become capable of igniting the tubes 8 and 9 when it discharges through their electrodes 15 and 16. Under these conditions, it is obviously impossible for the solenoid 4 to cause a second reclosure of the circuit interrupter 1 until the manual switch 21 has been reopened. This prevents the repeated reclosures and reopenings known as "pumping."

It will be noted that the source 6—7 impresses voltage at all times between the anode and the cathode of each of the ignitrons 8—9, and although such electrical discharge tubes are supposedly to remain non-conductive as long as no current flows through their igniter electrodes, it is found in actual practice that in long intervals for some causes which are difficult to explain they tend to acquire conductivity which, unless followed up by substantial current flow, persists for only an extremely brief instant. If only a single

ignitron were used in series with the solenoid 4, acquisition by this single ignitron for conductivity for even such a brief instant would be followed up by current flow from the source 6-7 and thus the circuit interrupted which might be closed unexpectedly without operation of the manual switches, such as 19 or 21 in the igniter circuit. While such random and brief acquisitions of conductivity by the ignitrons occur only at very long intervals, it is often desired that a circuit interrupter shall remain open for days at a time and the occurrence of one of these random brief intervals at any time within that long period would unexpectedly close the circuit breaker, with possible disastrous results to men working on the line 2. When, in accordance with my invention, two ignitrons connected in series with each other are used, the acquisition of conductivity for a brief interval by one will be incapable of causing substantial current flow through the solenoid 4 because of the fact that the other ignitron will be non-conductive. The latter fact will also prevent maintenance of conductivity in the first-mentioned ignitron by substantial current flow through the solenoid 4, and will permit the random conditions to cause reacquisition of the non-conductive state after an extremely brief interval. The probability that the brief random conductive state will occur simultaneously in the two ignitrons is so extremely small as to be utterly negligible. Hence by employing two ignitrons in series, I insure against any accidental closure of the circuit breaker 1 while the manually operated switches 19 and 21 remain open.

Referring now to the modification of my invention shown in Fig. 2, the source of supply of energizing current for the circuit breaker closing-solenoid 4 is an alternating current line 41-42. As in the case of Fig. 1, the closing solenoid 4 is connected to the line 41-42 through a pair of serially connected ignitrons 8-9, and in this case these ignitrons rectify the alternating voltage across the lines 41-42 so that the current flowing through the solenoid 4 is pulsating direct current. The ignitrons 8-9 are bridged by resistors 11-13, the same as in Fig. 1, and the igniter electrode 16 of tube 9 is connected to its anode through a switch 19 as in the case of Fig. 1. The igniter electrode 15 of tube 8, however, is likewise connected through a switch 21 as in Fig. 1 but in this case the other terminal of the switch 21 is connected through a pair of similarly poled rectifiers 43-44 to the line 42 to which the cathode 14 of the ignitron 9 is connected. It will be observed that the rectifier 43 is so poled that current flows into the cathode 13 of tube 8 from its igniter electrode 15 in the same direction as current flows into that cathode from its associated anode 11.

The common terminal of the rectifiers 43-44 is connected through a switch 45 which is manually operated in synchronism with the switches 19-21 and thence through a second switch 46 which is closed while the circuit breaker 1 is open and is open while the circuit breaker 1 is closed, thence through the secondary winding 48 of a transformer and a current limiting resistor 49 back to the supply line 42. A primary winding 51 connected across the supply lines 41-42 cooperates with the secondary winding 48. The circuit breaker 1 is provided with a latch 34 and an overload relay 35 which are the same as those in Fig. 1.

The mode of operation of the device in Fig. 2 is as follows. As long as the manually operated

switch 19-21-45 remains open no current flows through the igniter electrodes 15-16 of the ignitrons 8-9 and the solenoid 4 remains unenergized. When the manually operated switches 19-21-45 are closed, current can flow from the secondary winding 48 through the contacts 46 (which are closed because circuit breaker 1 is open) through the switch 45, rectifier 43, switch 21, igniter electrode 15, switch 19, igniter electrode 16, line 42 and current limiting resistor 49. The voltage of secondary winding 48 and current limiting resistor 49 are so proportioned that the current thus flowing is sufficient to energize igniter electrodes 15-16 to render ignitrons 8 and 9 conductive. Once the ignitrons 8-9 are rendered conductive current can flow from line 41 to line 42 through solenoid 4 and the two ignitrons. However, this current flow will continue for only one-half cycle of this alternating voltage on lines 41-42, the reversal of this voltage stopping all current flow through the ignitrons 8-9. The current flow through ignitrons 8-9 and solenoid 4 will, however, be resumed on the next half cycle of voltage provided the manually operated switch 19-21-45 remains closed and half-cycles of current will thus flow through solenoid 4 until circuit breaker 1 is moved to circuit closing position. When this happens switch 46 opens and cuts off current flow through the igniter electrodes 15-16 from the secondary winding 48. This condition persists as long as latch 34 maintains circuit breaker 1 closed even though the manually operated switch 19-21-45 is held closed.

It will be noted that the rectifier 44 permits current to flow in the opposite direction through secondary winding 48 from that half cycle which has already been described as flowing through secondary winding 48 and rectifier 43. Since alternate half cycles of current can flow through the secondary winding 48, no saturation results therein such as would occur if rectifier 43 alone were used in the circuit.

It will be noted that the presence of two ignitrons 8-9 in the Fig. 2 arrangement acts to prevent accidental closure of the circuit breaker 1 resulting from random ionization of one ignitron for a brief interval in the same way as has already been described in the case of ignitrons 8-9 in Fig. 1.

Fig. 3 shows how a single tube can be arranged to perform the same functions as the two ignitrons 8 and 9 were employed for in the case of Figs. 1 and 2. This figure shows the arrangement using an alternating current supply line similar to that in Fig. 1. The circuit breaker closing solenoid 4 is connected from one supply line to the other through a single ignitron tube 61 which is provided with an anode 62, a cathode 63 and an igniter electrode 64, and a shield electrode 65. The igniter electrode 64 is connected through a pair of similarly poled rectifiers 66-67 to the alternating current supply line 42 which is connected to the cathode 63 of the ignitron 61. The common terminal of the rectifier 66-67 is connected through a manually operated switch 68 and a switch 46 which is closed while the circuit breaker 1 is opened and is opened while the circuit breaker 1 is closed to the primary winding 48 of a transformer, the other terminal of which is connected through a current limiting resistor 49 to the line 42. The secondary winding 48 is energized from a primary winding 51 which is connected across the lines 41-42. The shield electrode 65 is connected to one terminal of a switch

69 which is closed simultaneously with switch 68 and thence through a resistor 71 to line 42. The shield electrode 65 is likewise connected through a switch 72 which is closed while switch 69 is open and is open while switch 69 is closed to one terminal of a capacitor 73, the other terminal of which is connected to the line 42. The capacitor 73 is bridged by a resistor 74 in series with a bias source 75 which tends to make the shield electrode 65 negative relative to its cathode 63.

The circuit breaker 1 is provided with a latch 34, an overload relay 31 in the case of Figs. 1 and 2.

When the circuit breaker 1 stands in open circuit position, the manually operated switches 68 and 69 are opened and the switches 72 and 46 are closed. The switch 68 prevents current flow from the secondary winding 48 to the igniter electrodes 64 until the manually operated switch is moved to closed circuit position. Hence the ignitron 61 is non-conductive and no current can flow through the solenoid 4. To move the circuit breaker 1 to its closed circuit position the manually operated switches 68-69 are closed and current then flows from the secondary winding 48 through closed switches 46-68, rectifier 66, and igniter electrode 64 thereby rendering the ignitron 61 conductive. Current then flows through solenoid 4 and closes circuit breaker 1 whereupon switch 46 is opened and ignitron 61 is deenergized in accordance with the description of ignitrons 8 and 9 in Fig. 2. It will be noted that switch 72 connects shield electrode 65 through bias battery 75 to the cathode 63 as long as manually operated switch 72 is closed thereby imposing a strong negative bias on the shield 65 which is sufficient to insure against the appearance of any such random brief intervals of conductivity in the space between the anode and cathode of the discharge tube 61. Thus while only a single ignitron is used in this system, none of the difficulties which made it necessary to employ two ignitrons in series, as described in Fig. 2, will be met with. When the manual switches 68 and 69 are closed to energize the igniter electrode 64, this negative bias on the shield electrode 65 is removed by the opening of switch 72. It will be observed that when the manually operated switch 68-69-72 is actuated to close circuit breaker 1, switch 69 connects the shield electrode 65 to the line 41 which is nearest in potential to the anode of tube 61, thereby removing any negative bias from shield electrode 65 and insuring free conduction in ignitron 61.

It will be noted that the circuit 73, 74, 75, 72, 69, 71 which is connected to the shield electrode 65 is merely connected across the supply line 41-42 while the circuit 66, 67, 68, 46, 48, 49 is the means for energizing the igniter electrode 63, and that these two circuits are entirely separate from each other. It is accordingly possible to employ the circuit comprising elements 73, 74, 75, 72, 69 and shield electrode 65 connected across a direct-current supply line such as that shown in Fig. 1 in just the same way as it is employed across the supply line 41-42 in Fig. 3. On the other hand, the control circuit for the igniter electrode 64 may have substituted for it an igniter electrode control circuit such as is shown in Fig. 4 with the result that a single igniter tube may be employed with a direct-current supply source.

Referring in detail to Fig. 4, a circuit breaker 1 is provided with a closing solenoid 4 which is supplied with current from direct-current line 75

6-7 through a single electrical discharge tube 61 which is preferably of the ignitron type provided with a shield electrode 65 similar to that described in connection with Fig. 3. The shield electrode is connected through a switch 69 which is normally open and through a resistor 71 with the positive side of the supply line 6-7 to which one terminal of the solenoid 4 is likewise attached. The shield electrode is likewise connected through a switch 72 which is closed while the switch 69 is open and is open when the switch 69 is closed to one terminal of a capacitor 73 of which the other terminal is connected to the negative supply line 7. The capacitor 73 is bridged by a resistor 74 and a bias source 75 having its positive terminal connected to the supply line 7. It will be seen upon examination that the connections so far recited for the shield electrode 65 are the same as the connections for the shield electrode 65 in Fig. 3.

The igniter electrode 64 of the ignitron 61 is connected through a resistor 76 to one terminal of a switch 21 which is operated in synchronism with the above-mentioned switch 69 and is open when the latter is open. The other terminal of the switch 21 is connected to the common terminal of a resistor 22 and a capacitor 23 which are serially connected with each other across the supply line 6-7. The capacitor 23 is bridged by a switch 25 which is connected to the circuit breaker 1 and is open when the latter is opened and closed when the latter is closed.

The anode 62 of the ignitron 61 is connected through a capacitor 26 to the common terminal 35 of a pair of resistors 27-28 which are connected in series with a switch 29 to the cathode of the tube 61. The switch 29 is connected to the circuit breaker 1 too but open when the latter is opened and closed when the latter is closed. 40 The circuit breaker 1 is likewise provided with a latch 34 under control of an overload relay the same as the circuit breaker described in Fig. 1.

When the circuit breaker 1 is open and it is desired to close it, the manually operated switches 69, 21 which are normally held in open circuit position are closed, thereby opening the switch 72. Opening the switch 72 disconnects the shield electrode 65 from the bias source 75 which normally maintains it at a potential sufficiently highly negative relative to its cathode 63 that there is no danger of spontaneous and random ionization of the space between the anodes 62 and 63. Closure of the switch 69 connects the shield electrode 65 to the positive line wire 6 and causes the capacitor 23 to discharge through the igniter electrode 64 and ionize the tube 61 in the same manner as discharge of the capacitor 23 in Fig. 1, has already been described as energizing the igniter electrodes of the tubes therein. In consequence of this alternation the potentials of its igniter and shield electrode tube 61 is rendered conductive and current flows from the line 6 through the solenoid 4 and ignitron 61 to line 7.

The circuit breaker is thereby moved to closed circuit position thereby in turn closing the switch 25 to shunt circuit capacitor 23 and closing the switch 29 to discharge capacitor 26 in reverse direction through ignitron 61 just as capacitor 26 has already been described as discharging through, and quenching, the ignitrons 8 and 9 in Fig. 1. No further detailed description of Fig. 4 is believed to be necessary in view of the similarity of its elements to those already described in Fig. 1.

I claim as my invention:

1. In combination with a circuit interrupter, a closing solenoid having one terminal connected to a supply line and its other terminal connected through a pair of serially connected electrical discharge tubes, to the other side of said supply line, said discharge tubes being each provided with a starting electrode, and auxiliary means including switching means for rendering both said discharge tubes conductive.

2. In combination with a circuit interrupter, a closing solenoid having one terminal connected to a supply line and its other terminal connected through a pair of serially connected electrical discharge tubes, to the other side of said supply line, said discharge tubes being each provided with a starting electrode, and auxiliary switching means for discharging a condenser through said starting electrodes to render said discharge tubes conductive.

3. In combination with a circuit interrupter, a closing solenoid having one terminal connected to a supply line and its other terminal connected through a pair of serially connected electrical discharge tubes, to the other side of said supply line, a pair of similar impedances respectively connected in multiple with said discharge tubes, said discharge tubes being each provided with a starting electrode, and auxiliary means including switching means for energizing said control electrodes to render both said discharge tubes conductive.

4. In combination with a circuit interrupter, a closing solenoid having one terminal connected to a supply line and its other terminal connected through a pair of serially connected electrical discharge tubes, to the other side of said supply line, a pair of similar impedances respectively connected in multiple with said discharge tubes, said discharge tubes being each provided with a starting electrode, and auxiliary switching means for discharging a condenser through said starting electrodes to render said discharge tubes conductive.

5. In combination with a circuit interrupter, a closing solenoid having one terminal connected to a supply line and its other terminal connected through a pair of serially connected ignitrons to the other side of said supply line, said ignitrons being each provided with a discharge electrode, and auxiliary means including switching means for discharging a condenser through said discharge electrodes to render said ignitrons conductive.

6. In combination with a circuit interrupter, a closing solenoid having one terminal connected to a supply line and its other terminal connected through a pair of serially connected ignitrons to the other side of said supply line, said ignitrons being each provided with a discharge electrode, and manually operated means for discharging a condenser through said starting electrodes to render said ignitrons conductive.

7. In combination with an electrical supply line, a circuit-breaker having an operating solenoid, said solenoid having one terminal connected to one side of said supply line and its other terminal connected through a pair of serially connected ignitrons, to the other side of said supply line, said ignitrons being each provided with a starting electrode, and auxiliary means including switching means for energizing said control electrodes to render both said ignitrons conductive.

8. In combination with a circuit interrupter, a closing solenoid connected across a supply line in serial relation with two serially connected ignitrons each having a starting electrode, a resistance which is high compared with the sum of the resistances of said starting electrodes connected in series with a condenser across a voltage source, and a circuit including switching means for connecting said condenser in serial relation with both said starting electrodes.

9. In combination with an electrical load connected across a supply line in serial relationship with two serially connected ignitrons each having a starting electrode, a resistance which is high compared with the sum of the resistances of said starting electrodes connected in series with a condenser across a voltage source, and switching means for connecting said condenser in serial relation with both said starting electrodes.

10. In combination with a circuit interrupter, a closing solenoid connected across a supply line in serial relation with an ignitron having a starting electrode, a resistor connected in series with a condenser across a voltage source, and a switching means for connecting said condenser and said discharge electrode in serial relationship, said resistor having a resistance which is high compared with that of said circuit.
